UNITED STATES PATENT OFFICE.

ALBERT JOHN SMITH, OF EAST DULWICH, ENGLAND.

APPLIANCE FOR USE WITH SAUCEPANS AND THE LIKE.

No. 819,940.

Specification of Letters Patent.

Patented May 8, 1906.

Application filed June 1, 1905. Serial No. 263,900.

To all whom it may concern:

Be it known that I, ALBERT JOHN SMITH, a subject of the King of Great Britain and Ireland, and a resident of 50 Crystal Palace Road, East Dulwich, county of Surrey, England, have invented certain new and useful Improvements in Appliances for Use with Saucepans and the Like, of which the following is a specification.

10 This invention relates to an appliance for use with saucepans and the like, and has for its object to enable any-sized saucepan or pudding-basin to be used for cooking puddings, porridge, fruit, and the like by means 15 of steam; further, to dispense with the use of a cloth or cover to the basin when cooking and to facilitate the raising or lowering of said basin from or into said saucepan or the like, and, still further, to prevent the basin 20 or the like from touching the bottom of the pan, so avoiding cracking or burning.

In order that my said invention may be readily understood, reference is to be had to the following description and accompanying 25 sheet of drawings, in which—

Figure 1 is a sectional elevation of my device as applied to a saucepan and lid. Fig. 2 is an under side plan view of the bridge of said device, and Fig. 3 a plan view of the expanding band and its attendant loops or links.

Like letters of reference indicate corresponding parts in the several views.

In carrying my said invention into effect I form an adjustable metal or wire bridge-piece 35 of two members $a a'$, Figs. 1 and 2, spanning the inner side of any-sized saucepan-lid b and from which an ordinary pudding-basin c is suspended by means of an expanding metal band d , which encircles said basin and is connected with the bridge-piece $a a'$, fixed in the 40 lid b by means of hooks or links e and f . (See Fig. 1.)

The sections or members $a a'$ forming the bridge-piece I form slightly-curved at their 45 outer ends g , as in Fig. 2, and provide the same near said ends with loops h or their equivalents, from which the hooks or links e , engaging the links or hooks f of the expanding band d , are suspended. These sections I 50 bridge by a metal clip i and clamp said sections together therein by means of the screw-nut j .

The clip I so arrange at its ends that each section can be drawn or slid apart with the 55 curved ends g outward, as in Fig. 2. Thus when fixing said bridge-piece in position in

the lid of the saucepan each section is extended in and from the clip in reverse directions until said curved ends come into contact with and rest on the beading of said lid. 60 The clip is then locked in position, thereby firmly securing the bridge-sections in their relative positions.

The basin-suspending band d , Figs. 1 and 3, I form from a strip of metal and curve the 65 ends thereof upon each other until both ends meet and overlap, both ends being provided with collars k , through which the band when expanding or contracting slides. The hooks or loops f I may connect to the band by providing holes for said hooks or loops to engage in, or I may attach said hooks or loops to said band in any suitable manner.

In use the basin c is inserted in the band d , the same being of appropriate size to engage 75 with (spring fit) the top of the basin and under the rim thereof. Then by means of the links or hooks f said basin is connected with the links or hooks e of the bridge-piece $a a'$, already fixed in position in the lid b of the 80 saucepan, and lowered into position in the saucepan, as shown in Fig. 1, in such a manner—that is to say, according to the lengths of the links or hooks—that the basin does not touch the bottom of the saucepan m . 85

In a device constructed in accordance with my invention it is not necessary to employ a cloth over the top of said basin, and only a moderate amount of water, as indicated at n , is required, the cooking being effected by the 90 steam given off, and, further, by the basin being thus suspended all likelihood of the contents or basin being damaged is obviated.

Having now described my invention, what I claim, and desire to secure by Letters Patent, is—

In a cooking utensil the combination with the lid thereof of a bridge-piece formed of two members slidable one with the other, means for locking said members one with another and to the lid, a spring-band and means such as loops or hooks for readily suspending said band to bridge-piece or for disconnecting said band from bridge-piece substantially as described. 100 105

In testimony whereof I have affixed my signature in presence of two witnesses.

ALBERT JOHN SMITH.
